SOLID COMPOSITIONS USEFUL IN
DRY CLEANING

Leo Stolmeijer, Nijverdal, Netherlands, assignor to N.V. Industrieleen Handel Mij Senzora v/h A. J. Schoemaker & Zonen

2 Claims 10

ABSTRACT OF THE DISCLOSURE

The filter powder and components of the dry-cleaning bath, in addition to the solvent, are added to the bath as a single additive in solid form, containing 10-85% by weight of adsorbent, 5-70% by weight of detergent, 5-80% by weight of water, and 5-40% by weight of a finish for improving the hand of the dry-cleaned textile products, and more preferably 30-40% by weight of adsorbent, 15-17% by weight of detergent, 38-42% by weight of water, and 8-16% by weight of finish.

For the dry cleaning of textile products, such as fabrics and knitwear, use is made of solvents, such as hydrocarbons, and preferably halogenated hydrocarbons, in particular perchloroethylene and trichloroethylene.

So-called cleaning enhancers can be added to the solvents. These cleaning enhancers are in general liquid products containing detergents and, if necessary, solvents, such as halogenated hydrocarbons.

It is known that an improved cleaning effect is attained by adding water in conjunction with these cleaning enhancers to the solvent. Especially water-soluble stains are thus removed more effectively. The quantity of water, however, is dependent upon the type of textile material to be cleaned, for example wool, silk, cotton, etc., and in general varies between narrow limits. Too small a quantity of water results in insufficient cleaning, and too large a quantity of water produces great shrinkage.

In addition to the detergent and water, the dry-cleaning bath generally contains a finish for improving the hand of the cleaned textile products, which finish is usually added separately to the solvent.

Furthermore, it is known that the bath may also contain other substances, e.g. other textile aids, such as antistatic agents, which are usually added separately to the solvent.

Dry cleaning as a rule is carried out in an apparatus consisting of a vessel with a recycle line containing a filter on which a filter aid, such as diatomaceous earth, is present. Frequently the apparatus comprises a built-in water-measuring device and separate tanks for different auxiliary agents. When using this apparatus, the solvent is introduced into the vessel and the filter aid added to the solvent to coat the filter. The apparatus is filled with clothes. After this, the water, the liquid cleaning enhancer, the finish, and any other auxiliary agents that may be desired are measured and added.

Since in practice, dry cleaning is often performed by unskilled labor, errors tend to be made in measuring these components, which errors may result in serious damage to the textile material to be cleaned. Especially the measuring of water is often effected inaccurately and in the worker's own way.

An object of the present invention is the provision of compositions useful in dry cleaning, which contain all additives generally used in a dry-cleaning bath.

A further object of the present invention is the provision of solid compositions useful in dry cleaning, which are

2

easier and more accurate to measure than the liquid additives.

A still further object of the present invention is the provision of a simple method of preparing dry-cleaning baths eliminating errors by unskilled labor.

Other objects of the present invention will be apparent from the specification and claims.

It has been found that these objects may be attained by the solid compositions of the present invention, which contain at least a solid adsorbent in finely divided form, a detergent, water, and a finish for improving the hand of the dry-cleaned textile products.

These solid compositions may also contain other substances, e.g. solvents, dissolving agents, antistatic agents, optical bleaching agents, chemical bleaching agents, such as peroxides and sodium hydrosulfite, special stain-removing agents, such as cyclohexanone, lactic acid, and oxalic acid, hydrophobing agents, fire retardants, preservatives, bactericides, fungicides, insecticides, perfumes, etc.

These substances are known to those skilled in the art, and are described in the literature. Furthermore, the compositions may contain sweeteners, that is, acid-binding substances, which prevent the bath from becoming acidic during the dry-cleaning treatment, e.g. lime.

As these compositions may contain all the additives simultaneously, measuring is simplified. Moreover, measuring can be effected more accurately.

The packaging of these solid compositions is also simplified.

The adsorbents serve to coat the filter, which may contain in addition to the adsorbents of the composition, also additional filter aids.

The solid compositions preferably contain about

10-85% by weight of adsorbent

5-70% by weight of detergent

5-80% by weight of water, and

5-40% by weight of finish for improving the hand of the dry-cleaned textile products.

Particularly preferred are solid compositions containing about

30-40% by weight of adsorbent

15-17% by weight of detergent

38-42% by weight of water, and

8-16% by weight of finish for improving the hand of the dry-cleaned textile products.

According to the present invention, the solid-compositions are added to the solvents in different quantities depending upon the material to be cleaned. The quantity is preferably 1 to 10 parts by weight to 1000 parts by weight of solvent.

Any adsorbent known in the art may be used.

Examples of adsorbents which may be used in the compositions according to the invention are diatomaceous earth, silica, alumina, metal silicates, ground or fibrous asbestos, metal stearates, sawdust, cellulose powder, starch, powdered synthetic polymers, cellulose fibers, etc.

Any detergent known in the art may be used.

Examples of detergents which may be used in the compositions according to the invention are neutralized fatty acids, petroleum sulfonates, fatty alcohol sulfates, condensates of fatty acids, alkylaryl sulfonates, secondary alkyl sulfates, epoxyethane condensates, sulfuric acid esters of polyethylene-glycol compounds, quaternary ammonium compounds, etc.

Any finish for improving the hand of the dry-cleaned products known in the art may be used.

Examples of finishes for improving the hand of the dry-cleaned textile products which may be used in the compositions according to the invention are terpene resins,

urea formaldehyde resins, paraffin, polyglycols, lanolin, stearin, petroleum resins, alkyd resins, gum resins, waxes, etc. Paraffin and pico-pale resins are to be preferred.

Dry-cleaning compositions are known which contain, besides a detergent, an aggregating agent. The quantity of solid aggregating agent used, however, is relatively small. These known compositions therefore are not solid, but pasty. Moreover they do not contain any dressings.

The invention is further elucidated by reference to the examples given below which, however, should not be regarded as limiting its scope.

EXAMPLE I

For the preparation of a composition containing an adsorbent, a detergent, water, and a finish for improving the hand of the dry-cleaned products, the following components are mixed:

80 kg. of diatomaceous earth,
40 kg. of detergent (a mixture of 16 kg. of 60% petroleum sulfonate [mol. wt. 470], 16 kg. of 80% tetrapropylenebenzene sulfonate, and 8 kg. of nonylphenol-polyglycol ether containing 10 moles of ethylene oxide),
100 kg. of water, and
20 kg. of paraffin powder.

A solid powdery composition is obtained.

EXAMPLE II

For the preparation of a composition containing an adsorbent, a detergent, water, and a finish for improving the hand of the dry-cleaned products, the following components are mixed:

80 kg. of diatomaceous earth,
40 kg. of detergent (the same as in Example I),
100 kg. of water, and
40 kg. of "Picopale resin" sold by Esso (a saturated petroleum resin of alicyclic structure).

A solid powdery composition is obtained.

EXAMPLE III

For the preparation of a composition containing an adsorbent, a detergent, water, a finish for improving the hand of the dry-cleaned products, and an antistatic agent, the following components are mixed:

30% by weight of diatomaceous earth,
10% by weight of fatty acid diethanolamide,
30% by weight of water,
20% by weight of octyl phosphate, and
10% by weight of lanolin.

A solid powdery composition is obtained.

EXAMPLE IV

250 g. of the composition prepared according to Ex-

ample I are introduced into an apparatus for dry cleaning containing 400 l. of gasoline. Subsequently 25 kg. of woolen knitwear to be cleaned are introduced into the apparatus. Extremely good results are obtained in cleaning.

EXAMPLE V

500 g. of the composition prepared according to Example II are introduced into a dry-cleaning apparatus containing 400 l. of trichloroethylene. Subsequently 25 kg. of woolen men's wear are introduced into the apparatus. Very good results are obtained in cleaning, even with a very low filter pressure.

EXAMPLE VI

25 kg. of raincoats to be cleaned are introduced into a dry-cleaning apparatus containing 400 l. of perchloroethylene. Subsequently 1500 g. of the composition prepared according to Example III are added. The cleaned raincoats are extremely fresh and clean. In this case again, the filter pressure remains very low.

For the cleaning of the same quantity by weight of woolen men's wear or woolen knitwear, 750 g. and 375 g. respectively of the composition prepared according to Example I are added.

Having described my invention, I claim:

1. Solid compositions useful as a single additive to chlorinated hydrocarbon dry-cleaning solvent baths for textile products, consisting essentially of an intimate admixture of

10-85% by weight of finely divided solid adsorbent which is insoluble in chlorinated hydrocarbon dry-cleaning solvents

5-70% by weight of organic dry-cleaning detergent

5-80% by weight of water, and

5-40% by weight of finish which improves the hand of the dry-cleaned textile products, said finish being soluble in chlorinated hydrocarbon dry-cleaning solvents.

2. Compositions according to claim 1, consisting essentially of

30-40% by weight of said adsorbent

15-17% by weight of said detergent

38-42% by weight of water, and

8-16% by weight of said finish.
